(57) **CLAIM**

The ornamental design for a gas cooktop and control panel, as shown and described.

DESCRIPTION

FIG. 1 is a front perspective view of a gas cooktop and an exploded view of a control panel showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken line showing of the remainder of the cooktop and control panel is for environmental purposes only and form no part of the claimed design.
